UNITED STATES PATENT OFFICE.

CLARENCE H. WILKES, OF GLOVERSVILLE, NEW YORK, ASSIGNOR TO FREDERICK KLEIN, TRUSTEE.

SEWING-MACHINE.

1,233,428.

Specification of Letters Patent. Patented July 17, 1917.

Application filed September 22, 1915. Serial No. 51,925.

To all whom it may concern:

Be it known that I, CLARENCE H. WILKES, a citizen of the United States, and resident of Gloversville, county of Fulton, and State 5 of New York, have invented certain new and useful Improvements in Sewing-Machines, of which the following is a specification.

My invention relates more particularly to 10 sewing machines employing a tubular spindle for supporting the work. This type of machine is usually employed in the manufacture of gloves the spindle being adapted to enter the fingers of the glove while the same is being sewed. In this type of machine 15 the working surface of the end of the spindle is of necessity very small in area and for this reason it is necessary to provide a special means for feeding the work during the sewing operation.

20 The object of the present invention is to provide a suitable feeding mechanism adapted to resiliently press upon the upper face of the work and intermittently feed the same forward when the needle is withdrawn. 25 In adapting my device to this type of machine the presser-foot is made smaller and preferably rests upon the work at one side of the needle while the feed wheel, pressing upon the goods on the opposite side of the 30 needle, will act as presser-foot and feed the work as required. The presser-foot is mounted upon a rod in the usual manner and my feed device is also preferably mounted upon another rod slidable in the head of 35 the machine and means are provided for lifting both the presser-foot and the feed wheel from the work when it is desired to free the same for adjustment.

One form of my device is shown in the 40 accompanying drawings in which Figure 1 is a side elevation, partially in section of a glove sewing machine; Fig. 2 is an end elevation of the sewing machine head and spindle; Fig. 3 is a cross section of my feed 45 mechanism substantially at 3—3 of Fig. 4; Fig. 4 is a vertical cross section of my device separate from the machine; Fig. 5 is the top cover of the casing.

50 Referring to the drawings 1 represents the table or bed of the machine having mounted thereon the tubular spindle 2 in the end of which the needle reciprocates, there being a hook reciprocating up and down in the tubular spindle to assist in forming the 55 lock stitch substantially as shown and de-

scribed in my Patent No. 1,049,430 of January 7, 1913; the needle and my improved mechanism, associated therewith, are supported in the head 3 in the usual or any preferred manner and the various mechanisms are adapted to be operated by cams or other suitable devices in the usual or any preferred manner, these latter parts not being shown. The needle rod 4 is reciprocated in the head 3 in the usual manner, the needle 60 5 being adapted to enter the upper end of the spindle 2 and carry the loop of thread into the spindle where it may be grasped by the reciprocating thread hook (not shown) and looped over the shuttle to form the lock 65 70 stitch substantially as described in the above patent.

The work A is supported upon the end of the spindle and a presser-foot 6 is adapted to press on the work at one side of the needle substantially as indicated in Fig. 1 of the drawings. It will be noted that this presser-foot is extremely narrow and adapted to press upon the work at one side only of the needle, a spring being provided on 75 the presser-foot rod in the usual or any preferred manner to resiliently hold the presser-foot in contact with the work. On the opposite side of the needle from the presser-foot 80 85 6 I preferably mount a feed wheel 7, provided with teeth adapted to engage the upper surface of the work so as to feed the same across the top of the spindle support 2 during sewing operation. The feed wheel 2 is preferably slightly conical in shape so that, 90 while the face rests flat on the work the wheel is at an angle to the needle as indicated in Figs. 1 and 4 of the drawings, thus permitting the working face of the wheel to be brought close to the needle. A stud shaft 95 8 is connected with the wheel 7 and pivotally mounted in the lower end of the casing 9, the shaft 8 carrying on its opposite end a bevel gear 10 adapted to mesh with another bevel gear 11 connected with a shaft 12 preferably supported vertically in the casing 9 as indicated in Fig. 4. The upper end of the shaft 12 is provided with a ratchet wheel 13 in which a reciprocating pawl 14 is adapted to operate to turn the ratchet in 105 one direction and thereby, through the intermediate gearing, turn the feed wheel 7 to feed the work in the manner described. Any suitable connection between the driving mechanism of the machine and the pawl 110

feed for the ratchet 13 may be made but preferably I employ a bolt pawl 14 which is adapted to be spring pressed toward the ratchet 13 by the spring 15, the pawl being held in position in a slide block 16, the latter being adapted to reciprocate in a slot 17 in the upper end of the casing 9 substantially as indicated in Fig. 3 of the drawings. The slide block 16 is preferably provided with a vertically disposed hole in which the rod or stub 18 loosely fits, the stud being reciprocated in a direction parallel with the slot 17 in any suitable or preferred manner to reciprocate the slide block 16.

15 The top plate 9^a is adapted to hold the slide block 16 and the ratchet in place in the casing 9.

The casing 9 is preferably provided with an extending ear or lug 19 which, in the present instance, is secured to a vertically reciprocating rod 20 slidably mounted in the head 2 substantially as indicated in Fig. 2 of the drawings. A suitable spring is provided for resiliently holding the rod and the associated casing 9 and feed wheel 7 in its lowermost position with the feed wheel pressing against the work upon the spindle 2. It will be understood that by thus mounting the feed wheel it may be lifted out of contact with the work when it is required to adjust the same, the feed wheel in this instance acting as a presser-foot while adapted to be intermittently turned to feed the work forward as required. To accommodate the reciprocating movement of the feed wheel in the manner above described the transversely reciprocating stud 18 loosely fits in the hole in the reciprocating slide 16 so that the latter may be moved up and down the stud, the stud being disposed parallel with the rod 20 and its direction of the motion. The two positions of the feed wheel and the associated casing are indicated in Fig. 1 by the solid and dotted lines respectively.

It is desirable when adjusting the work on the spindle that the presser-foot and the feed wheel be simultaneously removed or lifted out of contact with the work in order that the same may be turned or adjusted to any desired position. Any suitable means may be employed for this purpose but preferably I have provided a lever 21 pivoted at 22 to the head of the machine and carrying a cam at 23 adapted to be brought into contact with a lever arm 24 pivoted at 25 to the head of the machine. The end of the lever 24 is adapted to lie under a lug or projection 26 secured to the reciprocating rod 20, the latter being the rod upon which the feed wheel mechanism is mounted. A similar lug 27 is secured to the rod 28 which carries the presser-foot 6, the lug or projection 26 being provided with an additional projection extending into the path of the

lug 27 so that the latter will be lifted when the former is lifted by operating the lever 21, the relative positions of these parts being indicated in Fig. 1 in normal and lifted position by the solid lines and dotted lines 70 respectively.

The operation of my feed device is quite simple, the wheel 7 being turned intermittently by means of a ratchet and pawl fed so as to feed the work forward or away 75 from the operator, as is usual in sewing machines. When it is desired to insert or remove the work or adjust its position on the spindle the lever 24 may be operated, thereby lifting the feed wheel and presser-foot 80 out of contact with the work so that the same may be adjusted.

Various modifications of the specific details of my mechanism may be made without departing from the spirit and scope of the 85 invention.

I claim:

1. In a sewing machine of the type described, the combination of a feed wheel, a movable casing for supporting said feed 90 wheel, a ratchet wheel in said casing, means coöperating with the ratchet whereby the feed wheel is adapted to feed the work.

2. In a sewing machine of the type described, the combination with a support for 95 the work of a feed wheel, a movable casing for supporting said feed wheel, a ratchet wheel in said casing, reciprocating means coöperating with the ratchet and means to actuate said reciprocating means whereby 100 the feed wheel is adapted to feed the work.

3. In a sewing machine of the type described, the combination with a support for the work, of a revolving feed wheel, a movable 105 casing having a slot, for supporting said feed wheel, a ratchet wheel in said casing, reciprocating means in said slot coöperating with the ratchet and means to actuate said reciprocating means, whereby the feed wheel is adapted to feed the work.

4. In a sewing machine of the type described, the combination with a tubular support for the work, of a revolving feed wheel, a ratchet feed therefor, a movable casing for supporting said feed wheel and ratchet, said 115 casing being movably mounted whereby said wheel may be lifted from the work and means for operating said ratchet, whereby the feed wheel is adapted to feed the work.

5. In a sewing machine of the type described, the combination with a support for the work, of a revolving feed wheel, a movable casing having a slot, for supporting said feed wheel, a ratchet wheel in said casing, a slide block in said slot coöperating with the ratchet and means to actuate said slide block whereby the feed wheel is adapted to feed the work.

6. In a sewing machine of the type described, the combination with a tubular sup- 130

- port for the work, of a toothed feed wheel adapted to contact with the work to feed the same, a ratchet wheel for intermittently turning said feed wheel, the planes of said feed wheel and ratchet being at an angle to each other, a casing in which said ratchet and feed wheel are revolvably mounted, means for resiliently depressing said casing with said feed wheel over said tubular support and means for operating said wheel to feed the work, substantially as described.
7. In a sewing machine of the type described, the combination with a tubular support for the work, of a toothed feed wheel adapted to contact with the work to feed the same, a ratchet wheel for intermittently turning said feed wheel, the planes of said feed wheel and ratchet being at an angle to each other, a casing in which said ratchet and feed wheel are mounted, means for resiliently depressing said casing with said feed wheel over said tubular support and means for operating said wheel to feed the work, substantially as described.
8. In a sewing machine of the type described, the combination with a support for the work, of a revolving feed wheel, a casing having a slot, for supporting said feed wheel, a ratchet wheel in said casing, a slide block in said slot having a bolt pawl adapted to coöperate with said ratchet and means to actuate said slide block, whereby the feed wheel is adapted to feed the work.
9. In a sewing machine of the type described, the combination with a support for the work, of a revolving feed wheel, a casing having a slot, for supporting said feed wheel, a ratchet wheel in said casing, a slide block in said slot having a resiliently actuated bolt pawl adapted to coöperate with said ratchet and means to actuate said slide block, whereby the feed wheel is adapted to feed the work.
10. In a sewing machine of the type described, the combination with a support for the work, of a revolving feed wheel, a casing having a slot, for supporting said feed wheel, a ratchet wheel in said casing, a slide block in said slot having a spring actuated bolt pawl adapted to coöperate with said ratchet and means to actuate said slide block, whereby the feed wheel is adapted to feed the work.
11. In a sewing machine of the type described, the combination with a support for the work, of a revolving feed wheel, a casing having a slot, for supporting said feed wheel, a ratchet wheel in said casing, a slide block in said slot having a spring actuated bolt pawl adapted to engage said ratchet and a reciprocating rod to actuate said slide block whereby the feed wheel is adapted to feed the work.

In testimony whereof I have hereunto set my hand.

CLARENCE H. WILKES.
